DISPENSING APPARATUS

Peter Lohn, New York, N. Y.

Application June 15, 1940, Serial No. 340,679

9 Claims. (Cl. 221—102)

This invention relates to improvements in liquid dispensing apparatus and has particular reference to a type of dispenser such as disclosed in my Patent No. 2,180,989, dated November 21, 1939.

In said patent, a liquid discharge chamber is provided with a valve controlled outlet through which liquid received in said chamber from a supply receptacle is discharged by the action of an ejector in the form of a reciprocating plunger. This plunger carries a valve operating cam which is effective, at the inception of the inward or operative movement of the ejector, to open the valve for said outlet so that the liquid in the chamber in front of the ejector can be forced through said outlet. At the completion of the discharge stroke of the plunger, it is restored to the normal position thereof, and during the initial state of this restoration said valve is held open by said cam thus permitting air to enter the chamber through said outlet until the valve is finally closed. The presence of air in the chamber mixed with the liquid therein has a tendency, upon subsequent actuation of the ejector, to prevent the discharge of a full, predetermined quantity of said liquid from the chamber.

The present invention is designed to overcome the above difficulty by preventing the admission of air into the discharge chamber upon the return stroke of the ejector to thereby establish at least a partial vacuum in said chamber which will aid in filling the latter with the desired quantity of liquid for the next discharge operation. In carrying out this purpose, it is proposed to effect a positive closing of the outlet valve immediately upon the ejection of a predetermined quantity of liquid from the chamber by the operation of the ejector. The position of the plunger at the instant that said quantity has been completely ejected is hereinafter referred to as the discharge position.

The inventive idea involved is capable of receiving a variety of mechanical expressions some of which, for purposes of illustration, are shown in the drawings wherein:

Figure 1 is a fragmentary elevation, partly in section, of one form of dispensing mechanism constructed in accordance with the invention.

Figure 2 is a section taken substantially on the line 2—2 of Figure 1.

Figure 3 is an enlarged longitudinal section taken through the liquid discharge chamber and showing the position of the ejector and outlet valve at the end of the discharge stroke of said ejector.

Figure 4 is a fragmentary elevation, partly in

section, showing the valve operating member carried by the ejector.

Figure 5 is a top plan view of a part of a coin controlled mechanism which cooperates with the plunger ejector in holding the same in the normal position thereof and in releasing said ejector so as to permit of a discharge operation.

Figure 6 is an elevational view, partly in section, of another form of dispensing mechanism the parts being shown in their normal position and at an instant that a coin is inserted in the mechanism for its release preparatory to a discharge operation.

Figure 7 is a view similar to Figure 6 showing the position of the parts at the end of the discharge stroke of the ejector.

Figure 8 is a section on the line 8—8 of Figure 6, showing the outlet control valve in its operated or open position.

Figure 9 is a fragmentary vertical section showing still another form of dispensing mechanism, with the parts in their normal position.

Figure 10 is a similar view showing the position of the parts at the end of the discharge stroke of the ejector, and

Figure 11 is a section on the line 11—11 of Figure 9.

Referring to the form of invention shown in Figures 1 to 5, the numeral 12 indicates a cabinet or casing which is provided in the bottom thereof with an outlet well 13 through which a liquid or cream may be discharged into the hand by the operation of the dispensing mechanism. Within said casing 12 there is mounted a supporting block 14 in the lower end of which there is provided a horizontally disposed discharge chamber 15 in which the ejector 16 is mounted for reciprocation to discharge a predetermined quantity of liquid from the chamber 15 through the outlet 17 formed in the bottom of the block 14 and communicating with said chamber. Within said outlet 17 and partially encircled by the well 13 is an outlet valve casing 18 through which the liquid passes as it is discharged from the chamber. A vertically disposed needle valve 19 is slidably mounted in the block 14 with its lower end projecting into the casing 18 to normally close the valve seat therein, and with its intermediate portion extending transversely through the chamber

15. The upper end of the needle valve 19 is slidably disposed in the block 14 and is yieldably held in its normal or closing position by a coil spring 20 interposed between the upper end of the needle valve and a screw 21 threaded into the block 14. The ejector 16 fits snugly within the chamber 15

with its rear end projecting from the block 14 when the ejector is in its normal position, as shown in full lines of Figure 1. The forward end of the ejector is provided with the cup washers 22 which are utilized for the purpose of rendering the chamber 15 air tight. The forward end of the ejector also carries a valve actuating element, generally indicated by the numeral 23. This element is preferably formed from a thin flat strip of resilient material, such as spring steel, and is bent at one end to provide a flange 24 by means of which the element is secured to the ejector by a screw 25. Adjacent the flange 24, the element 23 is provided with a horizontal portion 26 and from this portion 26 to the forward extremity of the actuator 23 the same is downwardly inclined to provide a cam portion 27. This portion 27 is bifurcated to form a longitudinal slot 28 of sufficient width to receive the portion of the needle valve 19 located within the chamber 15. The slot 28 extends partially into the portion 26 of the actuator 23 and in the latter portion said slot terminates in an enlarged opening 29. The construction of the actuator 23, as described, is such that when the ejector 16 is moved inwardly or forwardly, to discharge a predetermined quantity of liquid from the chamber 15, the valve stem 19 will enter the forward end of the slot 28 and the upper surface of the cam portion will immediately contact a flange 30 formed on the needle valve. As the forward movement of the ejector progresses, said flange will ride upwardly upon the cam portion 27 with the result that the valve 19 will be lifted against the tension of its spring 20, thus raising said valve off of its seat and permitting the liquid to be forced through the valve casing 18 by the pressure of the ejector 16. As the ejector approaches the forward extremity of its movement the flange 30 will engage on top of the horizontal portion 26 of the actuator and immediately thereafter, that is when the ejector has reached its discharge position, the flange 30 will enter the opening 29 in the actuator 23. Thereupon, the spring 20 becomes effective to force the needle valve 19 downwardly, with the flange 30 passing through the opening 29, and the needle valve will then be restored to its normal position to shut off further egress of the liquid from the chamber 15 before the ejector 16 starts its return movement. With some liquid still remaining in the outlet 17, it will be obvious that when the valve 19 is again closed the admission of any air upwardly into the chamber 15 will be prevented. Valve 19 being now in its closed position, the flange 30 thereof will be positioned below the actuator 23 and thus be in the path of movement of the cam portion 27 of said actuator as the ejector returns to its normal position. However, due to the resiliency of the actuator 23, the latter will ride over the flange 30, as indicated in Figure 3, and the return movement of said ejector will therefore not be hindered. This return movement of the ejector is utilized to create a vacuum in the forward end of the chamber 15 which will be sufficient to again fill the chamber 15 in front of the ejector with another predetermined amount of liquid by the suction created at the liquid inlet 31 located at the forward end of said chamber. A supply pipe 32 has its lower end communicating with the inlet 31 and extends diagonally upward alongside of the block 14 to a point where the upper end of said pipe extends into said block and communicates with a nipple 33 therein to which is connected a supply re-

ceptacle or reservoir 34 from which the liquid is fed into said pipe.

The mechanism for actuating the ejector 16 will now be described. Said element is retained 5 in its normal position and restored thereto under the influence of two coil springs 35 connected to opposite sides of the rear end of the ejector and also to a bracket 36 secured to the bottom of the casing 12. On a bracket 37 secured to the block 10 14, there is pivoted a lever 38 the lower end of which is operatively joined to the rear end of the plunger by a link or pin 39. The upper end of the lever 38 is arranged in the path of a plunger 40 extending through a wall in the casing 12 and slidably mounted in the block 14. As the plunger 40 is pressed inwardly it contacts the upper end of the lever 38 and swings the same about its pivot so that a forward motion will be transmitted to the ejector 16 to force liquid from the chamber 15. The inward movement of the plunger 40 is limited by contact of a pin 41 thereon with a block 14.

When the plunger 40 has been released, after 25 being pressed inwardly to the limit of its movement, the springs 35 become effective to restore the ejector to normal and to reverse the movement of the lever 38 so that the plunger 40 will be forced outwardly to the position of Figure 1.

A coin controlled mechanism is operatively 30 associated with the plunger 40 for the purpose of preventing inward movement thereof until such time that a coin is deposited into the chute 42. Located at the lower end of this chute and adapted to be contacted by the coin is one end of 35 a locking lever 43 pivoted to the block 14 at 44. The other end of said lever normally engages in a groove 45 formed in the plunger 40 so as to prevent inward movement thereof. The weight of the coin rocks the lever 43 to the dotted line position of Figure 2 until said lever contacts one arm 46 of a substantially U-shaped member 47 slidably mounted in the block 14, thus limiting the downward movement of said lever to a point where the coin will still be supported by said lever. However, as the plunger 40 is forced inwardly a flange 48 thereon comes into contact with the other arm 49 of said member 47 and forces the latter member rearwardly against the tension of a spring 50 until the free end of the arm 46 disengages from the lever 43, whereupon 45 the coin will swing said lever down about its pivot until the coin is released from the chute. The lever 43 then restores toward its normal position until the end remote from the chute 42 rests upon the plunger, and when the latter has been fully 50 restored to its normal position under the influence of the spring 35, said lever 43 will again engage in the groove 45 of the plunger and lock the same against operation until another coin is inserted into the chute.

In the form of the invention shown in Figures 6 to 8, 51 indicates a portion of a cabinet in the bottom of which is positioned the cylindrical discharge chamber 52 the outlet 53 of which is controlled by a vertically movable needle valve 54 normally held in its closed position relative to said outlet by the coil spring 55 at the upper end of said valve. Intermediate the ends of the chamber 52 the same is provided with an inlet 56 to which is connected one end of said feed pipe 57 the other end of which is joined to a liquid supply receptacle 58. Movable within the chamber 52 is the ejector 59 which has a normal position in said chamber wherein the lower end of the ejector is located slightly above

the inlet 56. This ejector is moved downwardly at the inception of a discharging operation, as will appear in the course of the description, to force a predetermined quantity of liquid from the chamber 52 and, at the same time, the valve 54 is raised to open the outlet 53 so as to permit egress of said liquid under the pressure of said ejector. The initial stage of this operation is shown in Figure 8 wherein the valve has been raised and the ejector is moving downwardly in the chamber 52. Also, in this operation, the valve 54 is closed at the conclusion of the discharge operation of the ejector, as illustrated in Figure 7. It will be noted with regard to the latter position that when the valve 54 is closed and the ejector has reached the extreme of its downward movement, the lower end thereof is spaced from the lower end of the chamber 52 thus leaving a small quantity of liquid within the chamber 52. This small body of liquid acts as an air seal to prevent the admission of air into the chamber 52 around the point of the needle valve.

For the purpose of operating the needle valve and ejector, as above described, there is mounted in one wall of the casing 51 a shaft 60 having a handle 61 on its outer end and carrying an oscillatory disk 62 at its inner end. In the normal position of this disk, as shown in Figure 6, a lug 63 on the periphery thereof engages an adjustable stop 64 carried by the casing 51 and the limit of movement of said disk, when operated, is controlled by a second adjustable stop 65, as shown in Figure 7. Pivots connected to the disk 62, as at 66, is a sectional end adjustable operating link 67 the lower end of which is connected at 68 to a swinging arm 69 pivoted at 70 to the casing 51. Within this arm is disposed a sliding spring pressed trip 71 which, in its normal position, has its outer end projecting from the arm 69 and arranged, when the arm 69 swings upwardly, to contact an abutment 72 on the needle valve 54 so as to lift said needle valve from its seat against the tension of the spring 55. This action occurs as the handle 61 is turned in the direction of the arrow indicated in Figure 6 and, as the lug 63 contacts the stop 65 during which movement the arm 69 is swung upwardly, the trip 71 will disengage itself from the abutment 72 and the needle valve 54 is thereupon restored to its closed position under the influence of the spring 55. At the same time that this operation is taking place, another link 73 pivoted to the disk 62 at a point diametrically opposite the pivot 66 is forced downwardly by the turning movement of said disk. The lower end of said link 73 is pivotally connected to a head 74 secured to the upper end of the ejector 59 whereby said ejector is forced downwardly in the chamber 52 against the tension of the spring 75 coiled about said ejector. When the handle 61 is released at the conclusion of a discharge operation, said spring 75 operates to restore the ejector 59 to its normal, raised position and also returns the disk 62 to the position of Figure 6.

The coin controlled mechanism may be employed to lock the disk 62 in its normal position and is effective to release said disk for turning movement upon deposit of a coin in the chute 76. When this is done, said coin engages one end of a pivoted locking member 77 the other end of which is normally engaged in a notch 78 formed in the periphery of the disk 62. The weight of the coin rocks the lever 77 to disengage it from said notch and a stop 79 on the

disk limits the downward swinging movement of the lever 77 to a point where the coin will be partially retained within the slot until the handle 61 is turned. When this occurs, the stop 79 moves downwardly away from the lever 77 and permits the coin to drop into a receptacle 80. This action is illustrated in the full and dotted lines of Figure 7 and, upon release of the coin, the lever 77 moves to the full line position in the latter figure so that its locking extremity will drop into the notch 78 upon the restoration of the disk 62 to its normal position under the influence of the spring 75. As the ejector 59 is restored to its normal position, a vacuum is created in the chamber 52 and when the lower end of said ejector reaches the inlet 66 said vacuum becomes effective to draw another supply of liquid from the reservoir 58 into said chamber preparatory to a subsequent operation of the mechanism.

Reference is now made to the form of the invention shown in Figures 9 to 11. Herein the apparatus comprises a casing 81 having a well 82 in the bottom thereof over which is horizontally disposed the discharge chamber 83 provided with an outlet 84 controlled by the vertically disposed needle valve 85 which is slidably mounted in the sleeve 86 extending upwardly from the chamber 83, and which is yieldably retained in its normal position under the influence of the spring 87 engaging an abutment 88 on said needle valve. The chamber 83 is mounted in a bearing 89 supported on the bottom of the casing 81, and said chamber is provided within said bearing with an inlet 90. A feed pipe 91 has one end connected to said inlet and its other end to a liquid reservoir 92 whereby the liquid from the latter will flow into the chamber. An ejector 93 is slidably mounted for reciprocation in the chamber 83 and, in its normal position of Figure 9, the inner end of the ejector exposes the inlet 90 so that a predetermined quantity of liquid may enter the chamber. The opposite end of the ejector 93 terminates in a plunger 94 which extends through the wall of the casing 81 so that pressure may be exerted upon said plunger to move the ejector to its discharge position against the tension of a spring 95 that is coiled about the ejector and interposed between a flange 96 at the adjacent end of the chamber 83 and a disk 97 at the inner end of the plunger 94.

Again, as in the previously described modifications, the needle valve 85 is raised at the inception of the inward movement of the ejector and when the latter reaches its discharge position, at which point a predetermined quantity of liquid has been forced through the outlet 84, said needle valve is restored to its closed position. To accomplish this result, use is made of a bell-crank lever 98 pivoted at 99 to a wall of the casing 81 and having the lower extremity of its arm 100 in contact with the disk 97 on the plunger 94 so that as said plunger is forced inwardly the lever 98 will be swung to the position of Figure 10 against the tension of a spring 101 connecting the other arm 102 of said lever with the bearing 89. The free extremity of the other arm 102 is recessed to receive a spring-pressed trip 103 similar to the trip 71. As the lever 98 starts its swinging movement under the influence of the plunger 94, said trip 103 engages the lower end of the abutment 88 and continued movement of said lever thus lifts the valve 85 from its seat. At the end of the discharge stroke of the ejector 93 the trip 103 disengages

from the abutment 88 and the spring 87 then restores the needle valve 85 to its normal closed position. After the discharge of the predetermined quantity of liquid through the outlet 84 and subsequent release of pressure against the plunger 94 the spring 95 restores the ejector to its normal position and as soon as the inner end of the ejector reaches the inlet 90, during this movement, the vacuum created within the chamber 83 acts to draw another charge of liquid from the reservoir 92 into the chamber 83. The return of the ejector to its normal position permits the spring 101 to also restore the lever 98 to its normal position.

What is claimed is:

1. In a liquid dispensing apparatus, a liquid chamber having an outlet, a valve normally closing said outlet, an ejector movable in said chamber to a discharge position therein to force liquid therefrom and through said outlet, a valve opening element on said ejector operable, upon movement of the latter toward said discharge position, to engage and open said valve, said valve opening element being provided with means to release said valve for restoration to closed position when said ejector reaches said discharge position, and means to thereupon close said valve.

2. In a liquid dispensing apparatus, a liquid chamber having an outlet, a valve normally closing said outlet and having a stem provided with a cam engaging portion, an ejector movable in said chamber to a discharge position therein to force liquid therefrom and through said outlet, a cam extending from said ejector and being formed with a slot therein for receiving the stem of said valve, and being further formed with an opening at the inner end of said slot, said cam engaging said portion of said valve stem to open said valve at the inception of the movement of said ejector toward its discharge position, and said stem portion entering said opening at the conclusion of said movement to release said valve for restoration to its closed position, and means to thereupon close said valve.

3. In a liquid dispensing apparatus, a liquid chamber having an outlet, a valve normally closing said outlet and having a stem provided with a cam engaging portion, an ejector mounted for reciprocation in said chamber and having normal and discharge positions, a cam extending from said ejector and being provided with a slot therein for receiving the stem of said valve, and being further provided with an opening at the inner end of said slot, said cam engaging said portion of said valve stem to open said valve at the inception of the movement of said ejector toward its discharge position, and said stem portion entering said opening at the conclusion of said movement to release said valve for restoration to its closed position, means to thereupon close said valve, and means to return said ejector to its normal position after said valve is closed.

4. In a liquid dispensing apparatus, a liquid chamber having an outlet, a valve normally closing said outlet, an ejector movable in said chamber to a discharge position therein to force liquid therefrom and through said outlet, pivoted means movable into engagement with a portion of said valve to open the same upon inception of the movement of said ejector toward its dis-

charge position and disengaging from said valve portion at the termination of said movement to release the valve for restoration to closed position, and means to so restore said valve upon said disengagement.

5. In a liquid dispensing apparatus, a liquid chamber having an outlet, a valve normally closing said outlet, an ejector mounted for reciprocation in said chamber and having normal and discharge positions, a pivotally mounted valve actuating member movable into engagement with a portion of said valve to adjust the same to open position upon inception of the movement of said ejector from its normal position, said actuating member disengaging from said valve portion as said ejector reaches its discharge position, means to thereupon close said valve, and means to thereafter restore said ejector to its normal position.
